UNITED STATES PATENT OFFICE.

RUFUS RENIFF, OF BLOOMINGTON, ILLINOIS.

DESIGN FOR SAFETY-STIRRUP.

Specification forming part of Design No. **6,807**, dated August 19, 1873; application filed April 10, 1873.

To all whom it may concern:

Be it known that I, RUFUS RENIFF, of Bloomington, in the county of McLean and the State of Illinois, have invented a Design for Safety-Stirrups, of which the following is a specification:

My design consists in a net-work formed between the bottom and the top of the stirrups by curved and parallel bars, the spaces between the bars being diamond-shape, and diminishing in size at the top of the stirrup, as

fully represented in the accompanying drawing.

What I claim as my invention is—

The design for a safety-stirrup, in which the curved and parallel bars form a complete and ornamental net-work, as shown and described.

RUFUS RENIFF.
